UNITED STATES PATENT OFFICE.

JOHANN KONRAD LANGHARD, OF FREDRIKSSTAD, NORWAY, ASSIGNOR TO FREDRIKSSTAD ELEKTROKEMISKE FABRIKER A/S, OF FREDRIKSSTAD, NORWAY.

MANUFACTURE OF PERBORATES.

1,408,364.

Specification of Letters Patent. Patented Feb. 28, 1922.

No Drawing.

Application filed February 6, 1920. Serial No. 356,650.

To all whom it may concern:

Be it known that I, JOHANN KONRAD LANGHARD, a citizen of Switzerland, residing at Fredriksstad, Norway, have invented 5 certain new and useful Improvements in the Manufacture of Perborates; and I do hereby declare the following to be a full, clear, and exact description of the invention, such as will enable others skilled in the art to 10 which it appertains to make and use the same.

This invention relates to the manufacture of perborates by the electrolysis of aqueous borate solutions and has for its object an 15 improved method of treating the electrolyzed solution.

A known method of producing sodium perborate electrolytically consists in electrolyzing a solution containing borax and 20 soda (sodium carbonate).

In this process the sodium carbonate is gradually neutralized to bicarbonate in proportion to the formation of perborate.

The reactions taking place may be illustrated by the equation:

It has been ascertained that it is of importance to reconvert the resulting bicarbonate into carbonate in order to attain an advantageous current output. This may be effected by means of caustic alkali (NaOH) or lime.

It is an important condition of a satisfactory output, however, that the substances referred to are introduced in a state in which they are practically free from catalysts. To use chemically pure hydroxide of sodium 40 is of course not practicable, while on the other hand the commercial product usually contains small quantities of iron or even manganese compounds. The same applies also to lime. Under these conditions the 45 industrial value of the process is rather questionable. The present invention has for its object a process whereby the difficulties referred to are eliminated by simple and suitable means.

According to the invention the electrolyzed solution is treated with a peroxide instead of the hitherto employed substances, caustic soda or lime. Sodium peroxide is manufactured in a very pure condition practically free from injurious constituents and

when added to the electrolyzed solution it will have no disadvantageous influence upon the result.

The action of the sodium peroxide may be illustrated by the following equation: 60

The addition of the peroxide also results in the formation of additional quantities of 65 perborate as shown by the equation.

Experiments have proved that the precipitation of perborate by the addition of the peroxide is much more abundant than that obtained by cooling the electrolyte. The 70 advantages of the described process and its practical value are obvious.

Example: A hundred liters of an aqueous solution containing 40 g. borax, 100 g. soda, 7 g. perborate of sodium in the litre, and 75 which may consist of the mother liquor from a previous operation is subjected to electrolysis in a suitable apparatus with a current strength of for instance 120 amp. during for instance 4 hours. During the electrolysis the content of perborate will increase for instance to 12 g. of perborate in the litre, without crystallization taking place. At the same time an equivalent quantity of sodium bicarbonate has been formed. 85 To the liquid is now added sodium peroxide in a quantity of for instance 60 g. This addition of sodium peroxide on the one hand effects regeneration of carbonate and on the other hand results in such an increase in 90 the percentage of perborate, that precipitation of sodium perborate will begin. After some hours the crystallization of sodium perborate will be finished, without any considerable cooling of the liquid having taken 95 place.

The solution can now be subjected to electrolysis for the production of further quantities of perborate, it may be after having been supplied with an additional quantity 100 of borax.

The described treatment of the solution is suitably carried into effect in a separate vessel into which the solution is conveyed from the electrolytic cells. When the precipitated 105 perborate has been separated from the solution, this latter can be introduced into an electrolytic cell for further treatment.

Claims:—

1. Process for the manufacture of sodium 110

perborate, comprising in combination the steps of electrolyzing a solution containing borax and soda and adding sodium peroxide to the electrolyzed solution.

5. 2. Process for the manufacture of sodium perborate comprising the steps of subjecting a solution containing borax and soda to electrolysis, adding sodium peroxide to the electrolyzed solution, separating the precipitated 10 sodium perborate from the solution and subjecting the solution to electrolysis.

3. In a process of manufacturing sodium perborate, which consists in electrolyzing a solution containing borax and sodium car-

bonate, thereby obtaining a solution containing sodium perborate and sodium-hydrogen-carbonate, the improvement which consists in adding sodium peroxide to the resulting solution, thereby increasing the yield in sodium perborate and regenerating the solution in sodium carbonate. 20

In testimony that I claim the foregoing as my invention, I have signed my name in presence of two subscribing witnesses.

JOHANN KONRAD LANGHARD.
